UNITED STATES PATENT OFFICE.

ANSLEY S. PORTER, OF FITCHBURG, MASSACHUSETTS.

METAL-CUTTING MACHINE.

1,172,831.

Specification of Letters Patent.

Patented Feb. 22, 1916.

Application filed December 16, 1914. Serial No. 877,557.

To all whom it may concern:

Be it known that I, ANSLEY S. PORTER, a citizen of the United States, residing at Fitchburg, in the county of Worcester and State of Massachusetts, have invented a new and useful Metal-Cutting Machine, of which the following is a specification.

This invention relates to machines for cutting metal and is especially designed for roofers and other workers in sheet metal.

One of the objects of the invention is to provide a durable and compact machine of this character which can be readily attached to any work bench and, while operated by hand, will positively grip the metal being acted on and feed it through the machine so as to produce a straight cut, there being a gage combined with the machine and which is capable of ready adjustment so as to insure cutting the metal to a proper width.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a vertical longitudinal section through the machine. Fig. 2 is a section on line A—B Fig. 1. Fig. 3 is a section on line C—D Fig. 1. Fig. 4 is an end elevation of the machine. Fig. 5 is an enlarged vertical transverse section through one of the bearings. Fig. 6 is a face view of one of the cutters.

Referring to the figures by characters of reference 1 designates the base of the machine adapted to be bolted or otherwise secured upon a bench or the like and provided, at one end, with a post 2 having an integral arm 3 extending from the upper end thereof and parallel with the base 1. Standards 4 are integral with the base and support a table 5 which extends through the space between the base and the arm 3. This table 5 has a longitudinal series of apertures 6 and one end of the table is cut away as at 7 to receive the post 2 while the other end is cut away as at 8 to receive

the feed rollers hereinafter referred to. Journaled within and extending longitudinally of the base 1 is a shaft 9 to one end portion of which is secured a feed roll 10 having a reduced extension or boss 11 upon its outer face. Secured to this extension is a cutting disk 12 preferably held in place by means of several screws 13 projecting into the extension. The cutting edge of this disk 12 projects above the level of the table 5. That end of shaft 9 remote from the roll 10 is provided with a gear 13 and with a crank arm 14 or the like. This crank arm constitutes means whereby the mechanism is operated. Gear 13 constantly meshes with another gear 15 secured to one end of a shaft 16 which extends through a passage 17 formed longitudinally within the arm 3 and the upper end of post 2. Each end of the arm is provided with a guide-way 18 in which a bearing box 19 is slidably mounted, each bearing box being yieldingly supported, as by means of a spring 20 housed within the structure. Screws 21 are provided for engaging the upper ends of the boxes 19 for the purpose of adjusting them downwardly against the springs 20, thus to lower shaft 16. The teeth on the gears 13 and 15 are so shaped and proportioned as to permit a limited amount of movement of gear 15 toward and from gear 13 without disengaging the teeth.

That end of shaft 16 remote from gear 15 is provided with a feed roll 22 preferably faced with leather such as shown at 23. Secured to the outer side of this roll 22 is a cutting disk 24 designed to project between said roll and the inner face of the disk 12 and to fit snugly against the disk. The table 5 extends close to the disk 24 as shown in Fig. 1. Formed within the table 5 at opposite sides of the apertures 6 are parallel slots 25 and extending across these slots and resting on the table 5 is a gage strip 26 having bolts 27 which extend through the slots 25 so as to properly secure the strip to the table. Another bolt 28 is extended into any one of the apertures 6. The gage strip 26 has fingers 29 designed to overhang the near edge of the material being acted on.

In using the apparatus herein described, the gage strip 26 is adjusted along the table 5 until the distance between said strip and the disk 12 is equal to the width of the strip to be produced. The material to be

cut is placed on the table and against strip 26 and is pressed between the rolls 10 and 22. The leather facing of the roll 22 will yield to permit the material to be properly received between the rolls and said rolls will thus grip upon the material and, as shaft 9 is rotated, the said rolls will force the material across the table 5 and feed it properly to the disks 12 and 24. These 10 disks will shear the material along a straight line, the gage strip 26 properly guiding the material during the operation of cutting.

Importance is attached to the fact that the disks 12 and 24 can be removed readily 15 from the rolls for the purpose of sharpening or replacing them, and to the further fact that the rolls 22 and 10 can be quickly adjusted toward or from each other simply by manipulating the screws 21.

20 The entire structure is very simple, durable and compact and can be applied readily to an ordinary work bench so as thus to be especially designed for use by roofers and the like.

25 What is claimed is:—

A metal cutting machine including a base, a post at one side thereof, a tubular arm extending laterally from the upper end of

the post and overhanging the base, a shaft journaled within the base and extending 30 from one side to the other thereof, bearing boxes movably mounted within the end portions of the arm, a shaft journaled within the boxes and shiftable radially of the arm, said shaft extending through the arm, co-operating means upon the two shafts at one 35 end for transmitting motion from one shaft to the other, feed rolls connected to the shafts at their other ends and close to the base and the end of the arm respectively, 40 there being a concentric boss extending outwardly from one of the rolls, a cutting disk secured to said boss, another cutting disk secured to the other roll and extending back of the first mentioned disk, a table extending 45 between the arm and base and close to the inner sides of the rolls, and a gage strip adjustably mounted on the table and extending between the arm and base.

In testimony that I claim the foregoing 50 as my own, I have hereto affixed my signature in the presence of two witnesses.

ANSLEY S. PORTER.
